[57] ABSTRACT

There is disclosed a device for fixedly connecting panels for use in building of structures such as a wall board, a partitioning board or the like, in which sheets of panel are clamped by a shaped material made of a hard synthetic resin or a metallic material such as aluminum or the like, said shaped material being provided with recesses; a plug is fitted in each recess, said plug being made of a resilient synthetic resin or rubber and having a hole; and a wedge is inserted in said plug through said hole, thus panels being firmly connected and retained in place.

DEVICE FOR FIXEDLY CONNECTING PANELS FOR USE IN BUILDING

DESCRIPTION OF THE PRIOR ART

In the conventional method for connecting panels for use in building such as a wall board, a partitioning board or the like, connection of panels has been made by means of screws or nails. The method, however, results in such disadvantages that damage on panel is so frequent at the time of attachment, and when replacement of a panel is required due to damage thereon or change of facings, the topmost panel must be firstly removed prior to the panel to be replaced. Accordingly, either attachment or replacement of the panel is troublesome and takes much time.

SUMMARY OF THE INVENTION

A primal object of the present invention is to provide a device for fixedly connecting panels for use in building of structures such as a wall board, a partitioning board or the like, in which connection of panels is effected by means of a shaped material made of a hard synthetic resin or a metallic material such as aluminum or the like, a plug made of a resilient synthetic resin or rubber, and a wedge made of a hard material such as aluminum or the like, rather than by means of nails or screws, and therefore, there is no necessity for a tool.

Another object of the present invention is to provide a solid connection of panels which is performed by such a simple work that a plug is inserted in each of recesses formed at a shaped material and a wedge is driven into a hole of said plug, thereby firmly securing panels.

A further object of the present invention is to provide a device for fixedly connecting panels for use in building, wherein, when replacement of a panel is required due to damage on the panel or change of facings or the like, replacement is easily workable, with leaving other panels as they are.

A still further object of the present invention is to provide a device for fixedly connecting panels for use in building, which is capable of securing panels without hurting panels and without using a nail or a screw.

A still further object of the present invention is to provide a device for fixedly connecting panels for building use, in which the device is applicable for connecting any type of panel made of any kind of material and having any thickness; the practicality of the device is extremely widened; and a coupling member is concealed out of sight to enhance the appearance.

BRIEF DESCRIPTION OF THE DRAWINGS

FIG. 1 is a perspective view of a coupling member;
FIG. 2 is a perspective view of a holder member;
FIG. 3 is a perspective view showing a plug and a wedge;

FIG. 4 is a longitudinal sectional view taken along the line A—A of the plug;

FIG. 5 is a longitudinal sectional view taken along the line B—B of the plug;

FIG. 6 is a longitudinal sectional view showing a preferred embodiment of the present invention; and,

FIGS. 7 and 8 are longitudinal sectional views showing other embodiments of the present invention, respectively.

DETAILED DESCRIPTION OF THE INVENTION

A device for fixedly connecting panels for use in building consists of a coupling member 1, a holder member 2, a plug 3 and a wedge 4.

The coupling member 1 shown in the drawings is a shaped material made of a hard synthetic resin or metal such as aluminum or the like. Said coupling member 1 has a projection 5 and side arms 6, both being integrally formed therewith. Said projection 5 extends, for example, centrally from said coupling member 1 so as to partition a spacing between two arms into two groove-like recesses. Thus, the coupling member 1 presents an E-shaped cross section. Side arms 6 are bent at a right angle at their lower portions to extend outwardly to form retaining portions 8 thereat. An inside wall of each arm 6 is preferably provided with fine scores so as to perfectly prevent a holder member 2 from being frictionally slipped out therefrom when said holder member is fitted therein. Both side walls of projection 5 are also preferably provided with fine scores so as to firmly retain plugs 3 in place during a long period of service.

The holder member 2 is made of a hard synthetic resin or a metallic material such as aluminum or the like. Said holder member 2 is a shaped material having a L-shaped cross section and considering of a bent portion formed at one side to serve as a support piece 9 for carrying the panel sheet and the other side portion engagging the arm to serve as a holding piece 10.

FIGS. 3 through 5 show a plug and a wedge, in which said plug 3 is made of a resilient synthetic resin or rubber and provided at its upper head portion 11 with a hole 12, into which the wedge 4 is driven. The size and the shape of said hole substantially conform to the size and the shape of the wedge 4. Said plug 3 is split from the vicinity of the head portion 11 downwardly into two legs 13 with a spacing 14 interposed therebetween. The dimension of said spacing 14 formed between two legs 13 is smaller than the thickness of the wedge 4. Said spacing 14 is continuous to the hole 12 to form a guide spacing for the wedge 4. The plug 3 is fitted in each of recesses 7.

The wedge 4, as shown in FIG. 3, is made of a hard material such as aluminum or the like and has substantially a uniform thickness throughout. A catch 15 is provided at a head portion of said wedge 4 for the convenience of pulling out said wedge 4, after it has been fitted in the plug 3.

FIG. 6 shows panels in a connected condition.

In attachment, the coupling member 1 is fixed at its bottom face 16 by a bonding agent or screws to a pillar or the like, or both the upper and lower ends are secured by means of a separately prepared attaching component such as a L-shaped angle or the like to a ceiling, a floor board, a pillar, a wall board or the like. As an alternative, the coupling member 1, in addition to the afore-mentioned structure, may be provided with a support piece 17 integrally formed to extend from said bottom face 16 opposite to said projection 5, said support piece 17 being adapted to be connectable at its free end to other component by means of a bolt and a nut.

Otherwise, another projection 5, arms 6 and retaining pieces 8 may be integrally and symmetrically provided at the other end of said support piece 17. With such provisions, the coupling member 1 not only is connectable to any component such as a wall face, but also

is applicable to connect panels one upon another, thereby facilitating the formation of a double panel structure.

Thereafter, a sheet of panel 18 is placed with its surface engaging with the under side of retaining portion 8 of the coupling member 1, and then, the holder member 2 is inserted in the coupling member 1 with the upper side of support portion 9 abutting with the panel surface 18 as well as with the holder portion 10 engaging with the arm 6. Succeedingly, the plug 3 is fitted in the recess 7 and the wedge 4 is driven into the hole 12, thereby firmly securing the panel. It is good enough if several plugs 3 are fitted at a spacing from each other. A joint strip 19 is mounted on the outside of the plug 3.

In the embodiment illustrated in FIG. 7, the device for connecting comparatively a thick panel is shown, in which a groove is provided at the end face of the panel sheet 18 so as to insert the support piece 9 of holder member 2 therein.

The embodiment shown in FIG. 8 includes a deep bottom groove 20 provided at the bottom face 16 of coupling member 1, so as to permit connection of panels having a reduced or increased thickness, according to the depth of said groove 20.

What we claim is:

1. An adjustable device for securing panels in a building structure to accommodate panels of varying thicknesses comprising a coupling member having at least one rectangular smooth sided longitudinal groove; an L-shaped holder member with one leg of said member being smooth sided and adjustably receivable within said groove for sliding contact with a corresponding side of said longitudinal groove, and the other leg extending normally therefrom to receive and secure the edge of a panel between said normally extending leg and said coupling member; a plug insertable in said groove wherein the top surface of said plug is on line with or below the front face of said panel; and a wedge insertable in said plug to expand said plug against said holder member within said groove.

2. The device of claim 1, for use in combination with a panel member having a longitudinal groove in one edge thereof the same thickness as the thickness of said normally extending leg, wherein said normally extending leg of said holder member is forceably insertable in said panel member longitudinal groove for frictional engagement therebetween and to secure said panel member against said coupling member.

3. The device of claim 1, wherein said coupling member includes a leg normally extending outwardly therefrom adjacent the open end of said groove to form a smooth sided L configuration with a side of said groove wherein said panel is received between said normally extending leg and the normally extending leg of said holder member.

4. A device for fixedly connecting panels for use in building as set forth in claim 1 wherein said wedge is provided with a catch portion extending normally from the outer end thereof to limit the entry of said wedge into said plug and to provide means for extracting said wedge from said plug.

5. The device of claim 1, wherein said coupling member includes a second longitudinal groove parallel to and of the same definition as said first mentioned groove; a second L-shaped holder member of the same definition as said first defined L-shaped holder member

adjustably receivable in said second groove; and a second plug to grip said second holder member in said second groove, whereby a pair of panels are securable in edge to edge relationship.

5 6. An adjustable device for securing panels in a building structure to accommodate panels of varying thicknesses comprising a coupling member having at least one longitudinal groove; an L-shaped holder member with one leg of said member being adjustably receivable within said groove and the other leg extending normally therefrom to receive and secure the edge of a panel between said normally extending leg and said coupling member; a plug insertable in said groove; and a wedge insertable in said plug to expand said plug 10 against said holder member within said groove; said plug being formed with a head portion through which a hole is provided, and a pair of bifurcated portions extending downwardly from said head portion, said hole being adapted to receive said wedge therethrough.

15 7. An adjustable device for securing panels in a building structure to accommodate panels of varying thicknesses comprising a coupling member having at least one longitudinal groove; an L-shaped holder member with one leg of said member being adjustably receivable within said groove and the other leg extending normally therefrom to receive and secure the edge of a panel between said normally extending leg and said coupling member; a plug insertable in said groove; and a wedge insertable in said plug to expand said plug 20 against said holder member within said groove.

25 8. An adjustable device for securing panels in a building structure to accommodate panels of varying thicknesses comprising a coupling member having at least one longitudinal groove; an L-shaped holder member with one leg of said member being adjustably receivable within said groove and the other leg extending normally therefrom to receive and secure the edge of a panel between said normally extending leg and said coupling member; a plug insertable in said groove; and a wedge insertable in said plug to expand said plug 30 against said holder member within said groove; said coupling member including a second longitudinal groove parallel to said first mentioned groove; a second L-shaped holder member adjustably received in said second groove; and a second plug to grip said second holder member in said second groove, wherein said coupling member is E-shaped with three leg members supported by and extending normally from a common base member to form said first and second mentioned grooves; the center leg 35 of said legs extending beyond the two outer legs, and said two outer legs having panel holding flanges at their free ends and extending normally outwardly therefrom.

35 9. An adjustable device for securing panels in a building structure to accommodate panels of varying thicknesses comprising a coupling member having at least one longitudinal groove; an L-shaped holder member with one leg of said member being adjustably receivable within said groove and the other leg extending normally therefrom to receive and secure the edge of a panel between said normally extending leg and said coupling member; a plug insertable in said groove; and a wedge insertable in said plug to expand said plug 40 against said holder member within said groove; said coupling member including a second longitudinal groove parallel to said first mentioned groove; a second L-shaped holder member adjustably received in said second groove; and a second plug to grip said second holder member in said second groove, said coupling member being E-shaped with three leg members supported by and extending normally from a common base member to form said first and second mentioned grooves; the center leg of said legs extending beyond the two outer legs having panel holding flanges at their free ends and extending normally outwardly therefrom.

45 10. An adjustable device for securing panels in a building structure to accommodate panels of varying thicknesses comprising a coupling member having at least one longitudinal groove; an L-shaped holder member with one leg of said member being adjustably receivable within said groove and the other leg extending normally therefrom to receive and secure the edge of a panel between said normally extending leg and said coupling member; a plug insertable in said groove; and a wedge insertable in said plug to expand said plug 45 against said holder member within said groove; said coupling member including a second longitudinal groove parallel to said first mentioned groove; a second L-shaped holder member adjustably received in said second groove; and a second plug to grip said second holder member in said second groove, said coupling member being E-shaped with three leg members supported by and extending normally from a common base member to form said first and second mentioned grooves; the center leg of said legs extending beyond the two outer legs having panel holding flanges at their free ends and extending normally outwardly therefrom.

50 11. An adjustable device for securing panels in a building structure to accommodate panels of varying thicknesses comprising a coupling member having at least one longitudinal groove; an L-shaped holder member with one leg of said member being adjustably receivable within said groove and the other leg extending normally therefrom to receive and secure the edge of a panel between said normally extending leg and said coupling member; a plug insertable in said groove; and a wedge insertable in said plug to expand said plug 55 against said holder member within said groove; said coupling member including a second longitudinal groove parallel to said first mentioned groove; a second L-shaped holder member adjustably received in said second groove; and a second plug to grip said second holder member in said second groove, said coupling member being E-shaped with three leg members supported by and extending normally from a common base member to form said first and second mentioned grooves; the center leg of said legs extending beyond the two outer legs having panel holding flanges at their free ends and extending normally outwardly therefrom.

60 12. An adjustable device for securing panels in a building structure to accommodate panels of varying thicknesses comprising a coupling member having at least one longitudinal groove; an L-shaped holder member with one leg of said member being adjustably receivable within said groove and the other leg extending normally therefrom to receive and secure the edge of a panel between said normally extending leg and said coupling member; a plug insertable in said groove; and a wedge insertable in said plug to expand said plug 65 against said holder member within said groove; said coupling member including a second longitudinal groove parallel to said first mentioned groove; a second L-shaped holder member adjustably received in said second groove; and a second plug to grip said second holder member in said second groove, said coupling member being E-shaped with three leg members supported by and extending normally from a common base member to form said first and second mentioned grooves; the center leg of said legs extending beyond the two outer legs having panel holding flanges at their free ends and extending normally outwardly therefrom; and said base member being shaped to form

a third groove on the side opposite said leg supporting side to receive a support structure therein.

9. An adjustable device for securing panels in a building structure to accommodate panels of varying thicknesses comprising a coupling member having at least one longitudinal groove; an L-shaped holder member with one leg of said member being adjustably receivable within said groove and the other leg extending normally therefrom to receive and secure the edge of a panel between said normally extending leg and said coupling member; a plug insertable in said groove; and a wedge insertable in said plug to expand said plug against said holder member within said groove; said coupling member including a second longitudinal groove parallel to said first mentioned groove; a second L-shaped holder member adjustably receivable in said second groove; and a second plug to grip said second holder member in said second groove, said holder members being insertable to different depths in said coupling member grooves to secure panels of different thicknesses.

10. An adjustable device for securing panels of varying thickness in a building structure, each of said panels having parallel front and back surfaces and a longitudinal edge surface extending perpendicularly therebetween defining the panel thickness, and longitudinal front and back marginal edge portions on said front and back surfaces, respectively, adjacent said longitudinal

edge surface and extending laterally inwardly therefrom, the device comprising: a coupling member having at least one rectangular, smooth-sided longitudinal groove therein and a substantially rigid, flat lateral surface extending laterally from the open end of said longitudinal groove and parallel to the plane of said panel, said lateral surface facially contacting said back panel surface along said back marginal edge portion; and L-shaped holder member having a substantially rigid smooth-sided first leg being adjustable receivable within said groove and a substantially rigid second leg extending normally therefrom parallel to both said front surface of said panel and said flat lateral surface, said second leg having a face portion defined by the inside surface of the normally extending leg, facially contacting said front surface of said panel along said front marginal edge portion, said face portion and said flat lateral surface defining a closely fitting slot, said holder member holdably securing said panel in said slot along said front and back marginal edge portions of said panel; a retaining plug insertable in said groove to a depth below the surface of said panel, and a wedge insertable in said plug to expand said plug against said first leg of said holder member within said groove, thus retaining said holder member in said groove to secure said slot around said panel edge and marginal edge portions.
